Weidenschein & Linbeck

ATTORNEYS.

UNITED STATES PATENT OFFICE

RUDOLPH SCHATZ, OF PHILADELPHIA, PENNSYLVANIA

COMBINED WEIGHT CASH BOX AND ADVERTISING DEVICE FOR UNATTENDED NEWS STANDS

Application filed March 11, 1929. Serial No. 346,113.

My invention relates to a new and useful combined weight and cash box particularly adapted for use in connection with unattended news stands, to prevent the scattering of the news papers by the action of the wind and to insure against loss, whether by misplacement or pilferage, of the money paid by the public purchasing the news papers.

My invention further relates to a device 10 of this character, which in addition to weighting the news papers and safeguarding the money paid therefor, is also ornamental in appearance, and the construction of which lends itself to advertising if so desired.

As is well known, it is customary, especially 15 in the case of stores not specializing in news material, but carrying a side line of news papers and magazines and the like, to place such newspapers and magazines on a stand positioned outside of the store and altogether unattended, it being left to the customers to pay the price of the news paper and help themselves without any aid or attention. To 20 weight the papers down and prevent their being scattered by the wind, a stone, brick, horseshoe or the like was used, and in some cases, an old empty cigar box or other receptacle was also placed on the news papers or on the stand for the reception of the purchase 25 money, while in other cases the money was loosely deposited on the top of the stack of newspapers being sold. When no receptacle was employed, the pennies and other small coins left by the purchasers tended to roll 30 off the stand when another paper was being pulled out of the stack; while if a receptacle were employed, the collected coins constituted a severe temptation to youngsters and others, so that loss due to misplacement or 35 to pilferage was unavoidable.

To overcome these disadvantages, I have devised a novel combined paper weight and cash box which serves for weighting down the stack of newspapers to prevent their being scattered by the wind, and which affords a safe deposit or receptacle for the coins left by the public in payment for the newspapers, thus guarding against loss through theft or through the coins rolling off the stand and 40 being lost.

My novel combined paper weight and cash box in addition to possessing the advantages above mentioned further serves as an advertising device if so desired, by inscribing thereon the name of the news dealer, the name 55 of the newspapers being sold, or the name of some other product which it may be desired to advertise, thus substituting for the unsightly brick, stone, or other weight heretofore employed an ornamental and useful device. 60

To the above ends, my invention consists 65 of a container of any suitable form or size, and painted in any suitable color, a weight forming a bottom closure for said container, means for detachably but firmly securing said bottom to said container, slits in the top of said container for receiving coins in payment for the newspapers being purchased, means for preventing the unauthorized withdrawal of said coins from said container, and 70 means for firmly but detachably securing said container to the news stand or other fixed support.

My invention further consists of various 75 other novel features of construction and advantage all as hereinafter described and claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged 80 and organized and that my invention is not limited to the precise arrangement and organization of the instrumentalities as herein shown and described.

In the accompanying drawings:

Fig. 1, represents a perspective view of my 90 novel combined weight and cash box, the same being shown in actual use on a news stand.

Fig. 2, represents a top plan view of my 95 novel combined weight and cash box shown detached.

Fig. 3, represents a section on line 3—3 of Fig. 2, certain parts being shown in elevation.

Fig. 4, represents a top plan view of the bottom closure of my novel combined weight and cash box shown detached.

Fig. 5, represents a view in side elevation showing the manner of assembling the upper container portion and the weight forming the bottom closure therefor, the upper portion of the figure being broken away.

Fig. 6, represents a top plan view of Fig. 5. Referring to the drawings, in which like reference characters indicate like parts, 1 designates my novel combined weight and cash box shown in actual use on a stack of newspapers 2, placed on an outdoor, unattended stand 3. My combined weight and cash box 1 comprises the container 4, composed of the upright wall 5 which may be cylindrical or otherwise, the top or lid 6, permanently secured to or formed integral with the upright wall 5, and preferably overhanging the latter as at 7*. In the top 6 of the container 4 are the slits 7, through which the coin or coins deposited in payment for a newspaper or the like may be dropped. To prevent the withdrawal of the coins from the container 4, I provide the pendant teats 8, best seen in Fig. 3. The container 4 is closed at its bottom by the plate 9 having the upturned flange 10 which is adapted snugly to engage the bottom end of the upright wall 5 which is of slightly smaller overall dimensions. To the bottom wall or plate 9 is permanently secured the weight 12, such as a block of iron or lead, said weight being adapted to fill the lower portion of the container 4 and to extend to approximately the mid height thereof, the top surface of said weight serving to receive the coins dropped into said container, as will be understood from Fig. 3. 13 designates a horizontally disposed U-shaped bracket having the through aperture 14 therein, and secured to the bottom plate 9 by the pendant integral limb 15, as will be understood from Fig. 3. 16 designates a lip or tongue, permanently secured to the upright wall 5 of the container 4, and having the aperture 17 therein, said lip 16 being adapted to seat between the limbs of the U-shaped bracket 13, with the aperture 17 thereof aligning or registering with the aperture 14 in said bracket. The shackle 19 of a padlock 18 is then passed through the aligning apertures 16 and 14 and through the end link 20 of a chain 21, the other 22 of said chain being permanently anchored at the point 23. The padlock 18 thus secures the container 4 to the bottom closure 9 and secures the entire device to the news stand or other fixed support to safeguard against unauthorized removal. In order to facilitate the aligning of the aperture 17 in the lip 16 with the through aperture 14 in the limbs of the U-shaped bracket 13, I provide the notch 24 in the bottom edge of the upright wall 5 of the container 4, which is adapted to act as a stop for limiting the rotation of the

bottom closure 9 with respect to the upright wall 5 of the container 4 at the point at which the aperture 17 is in registering alignment with the aperture 14 in the U-shaped bracket 13.

The outer surface 25 of the container 4 is very well adapted for the inscription of an advertisement such as the name of the papers being sold, the name of a special product, or the name of the dealer, or any other desired information, thus increasing the utility and value of my novel device.

When it is desired to remove the coins from the container 4, the padlock 18 is unlocked, and the bottom closure 9 is revolved until the lip 16 is withdrawn from engagement with the U-shaped bracket 13, whereupon the container 4 is turned upside down to prevent the dropping out of the coins collected therein and the bottom closure 12 is withdrawn upwardly from the container 4. After the coins in the container 4 have been removed, the device is again assembled in the manner described and is ready for further use.

It will thus be seen that in addition to providing a weight for preventing the scattering of the papers by the wind, and in addition to anchoring said weight to prevent loss or misplacement thereof, I have further devised means for safeguarding against the loss of the money paid by the purchasing public, whether through accidental loss or through theft. It will further be seen that my novel weight and cash box also constitutes a very valuable and effective advertising medium since it is in constant sight of all passersby and since the attention of every person buying a newspaper is particularly and inevitably called to whatever is inscribed thereon. It will further be seen that I have devised an extremely simple, durable, and inexpensive device which can be profitably adopted and used wherever the sale of newspapers and the like is carried on without the aid and attention of constant attendant.

I am aware that the invention may be embodied in other specific forms without departing from the spirit or essential attributes thereof, and I therefore desire the present embodiment to be considered in all respects as illustrative, and not restrictive, reference being had to the appended claims rather than to the foregoing description to indicate the scope of the invention.

What I claim as new, and desire to secure by Letters Patent, is:

1. In a device of the character stated, a container, a permanent top closure therefor, having slots therein for the passage of coins therethrough into said container, a detachable bottom closure for said container, a weight carried by and secured to said bottom closure and adapted to extend upwardly within said container when said container and said bottom closure are assembled, and in-

terlocking devices common to said bottom closure and the lower portion of said container, for securing said bottom closure to said container.

5. 2. In a device of the character stated, a container, a permanent top closure therefor, having slots therein for the passage of coins therethrough into said container, means coacting with said slots to prevent withdrawal of said coins, a detachable bottom closure for said container, a weight carried by and secured to said bottom closure and adapted to extend upwardly within said container when said container and said bottom closure are assembled, and interlocking devices common to said bottom closure and the lower portion of said container, for securing said bottom closure to said container.

3. In a combined weight and cash box of the character stated, a container, a permanent top closure therefor, having slots therein for the passage of coins therethrough into said container, means coacting with said slots to prevent withdrawal of said coins, a detachable bottom closure for said container, a weight carried by and secured to said bottom closure and adapted to extend upwardly within said container when said container and said bottom closure are assembled, interlocking devices common to said bottom closure and the lower portion of said container, for securing said bottom closure to said container and a flexible connection having one end thereof engaged by said interlocking devices and the other end thereof secured to a fixed support, for preventing the unauthorized removal of said combined weight and cash box.

4. In a device of the character stated, a container, a slotted cover therefor, a closure for the bottom of said container, a weight superimposed upon said closure and extending upwardly within said container, a bracket carried by said closure, a lug projecting from said container, there being aligning holes in said lug and bracket, and a lock for said lug and bracket.

5. In a device of the character stated, a container, a permanent top closure therefor having slots therein for the passage of coins dropped into said container, means on the underside of said top closure coacting with said slots to prevent withdrawal of said coins from said container, a bottom detachable closure for said container, a weight carried by and secured to said bottom closure and adapted to extend upwardly into said container when the latter and said bottom closure are assembled, an apertured horizontally disposed lug carried by the lower portion of said container, a horizontally disposed U-shaped apertured bracket carried by said bottom closure and adapted to engage said lug when said container and said bottom closure are assembled, locking devices adapted to engage

the apertures in said lug and bracket to lock said bottom closure to said container, and a flexible connection having one end thereof engaged by said locking devices and the other end thereof anchored to a fixed support.
